OVERHEAD TROLLEY SYSTEM

Warren J. Lewis, Mansfield, Ohio, assignor to The Ohio Brass Company, Mansfield, Ohio, a corporation of New Jersey

Application April 3, 1942, Serial No. 437,556

5 Claims. (Cl. 191—38)

This invention relates to overhead trolley systems and in its more specific aspects is directed to a relay actuated switching device for current collectors.

The object of this invention is to construct a trolley frog whose tongue element is relay actuated and with which delaying mechanism is operatively connected to positively assure the actuation of the tongue shifting mechanism.

Another object of the invention is to provide a relay actuated tongue shifting device in which the vehicle current collectors selectively actuate said relay and in which an accidental reopening of the relay circuit is prevented until the vehicle has passed the trolley frog.

Another object of the invention is to construct a trolley frog whose tongue element is relay actuated and whose control circuit includes a safety device to insure a positive shifting of the tongue element.

A still further object of the invention is to provide a positively actuated relay type of trolley frog shifter and which will prevent unintentional operations thereof.

Another and still further object of the invention is to provide in a resetting relay type frog shifting device a control "circuit" that will shunt the relay such that any arc potential between collector and wire will not cause the relay to operate and shift the tongue element when such movement is not desired.

A still further object of the invention is to provide a trolley frog shifter that is relay actuated and in which the effect of any arc potential formed between the current collector and the trolley is completely eliminated.

Other and further objects of the invention will occur to those skilled in the arts to which this invention pertains as the description proceeds which taken in connection with the accompanying drawings sets forth a preferred embodiment of the invention and selected modifications thereof, but such disclosures are not to be construed as a limitation of the invention which is limited only by the appended claims and any and all modifications, alterations and variations of structure coming within the spirit and scope thereof are deemed to be included herein.

In the drawings:

Fig. 1 shows a schematic plan view of a preferred embodiment of the invention.

Fig. 2 shows a side elevational view of a modification of the invention.

Fig. 3 shows a schematic plan view incorporating the modification of Fig. 2.

Fig. 4 shows a detail sectional view along the line 4—4 of Fig. 2.

Fig. 5 shows a schematic plan view of a structural variation of the embodiment of Fig. 1.

The objects set forth above are embodied in the structure generally disclosed in Fig. 1 in which 1 and 2 designate conventional frog elements to which trolley wires 3, 3 are secured and from which wires 5, 5 are lead in a straight through direction and 4, 4 branch off as turn-off or curve wires. A tongue element 7 is arranged on each of the frog pans 1 and 2, pivoted thereto at 8, which selectively connects the wires 3, 3 to either 4, 4 or 5, 5 depending upon the adjusted position of the tongue elements 7, 7.

The moving vehicle (not shown) has the usual current collectors 9, 9a arranged thereon in the conventional manner that are adapted to engage the respective trolley wires 3, 3 and as indicated above, tongue elements 7, 7 direct the current collectors 9, 9a selectively on to the branch or curve trolley wires 4, 4 or the straight through wires 5, 5. In order to maintain the frog pans 1 and 2 in proper spaced relationship a pair of strain elements 6, 6 is arranged therebetween to maintain the said spaced relationship which is coincident with the spacing of the current collectors 9, 9a.

Means have been provided for the shifting of the tongue elements 7, 7 to line up with either of the wires 4, 4 and 5, 5, as indicated above, which means is embodied in a pair of actuating coils 11, 11, each of which has a plunger 14 that is mechanically linked to the tongue elements 7, 7 by a bar or linkage schematically shown at 15, 15. A latching means is shown at 15a, 15a pivotally supported at 16, 16 by means of bar elements 15b, 15b which are kept in a retracted position by means of springs 17, 17; each of the latch elements 15a, 15a receive the bar linkage 15 on one side of it when the switch is set for straight through and on its opposite side when set for curve. The particular illustration discloses a conventional re-set type of mechanism which originates in a pair of pivoted elements 12, 12 that are mechanically linked to the plungers 14, 14 of actuating coils 11, 11 by means of the linkage 13. Re-set mechanisms 12, 12 are engaged by the current collectors 9, 9a to restore the tongue elements 7, 7 to the straight through position following each passage of the vehicle to the turn-off position.

Arranged adjacent each of the trolley wires 3, 3 are contactors 10 and 10a that are placed on the approach side of frog pans 1 and 2 and

substantially opposite each other but each of which is of a different length, as indicated by the dimension "A" shown on the drawings. The length of distance "A" is a function of the length of the lead of contactor 9a over 9 and the speed or time of the vehicle in passing over the section of trolley in which the frog pans are arranged and must be of such an extent as will enable the switch coil 24 to close in order to complete the shifting of the switch element 26 to the turn-off position before collector 9 engages with contactor 10. The time interval required for shifting 26 must not exceed the time interval it takes collector 9a to travel the lead distance of 9a over 9 less distance "A." In the normal operation of the vehicle while turning it will cause collector 9a to advance much more rapidly than collector 9 will advance and thereby bring it into contact with contactor 10a before collector 9 engages with contactor 10. The engagement of collector 9a with contactor 10a establishes a circuit through conductors 18, 18a, resistance 23, coil 24, and conductor 25 to the opposite trolley wire 3, it being noted that one of these trolley wires is the positive and the other is the negative wire. The circuit just described is completed in order to shift switch 26 by means of coil 24 from the full line position to the dotted line position in Fig. 1 and constitutes a holding circuit therefor until broken by collector 9a leaving contactor 10a. Following the closing or shifting of switch 26 to the dotted line position, a circuit is established through the actuating coils 11, 11 as follows: wire 3, collector 9a, contactor 10a, conductor 18 thence by means of conductor 19 through the coil on one of the actuators 11, conductor 20 and thence through to switch 26 and conductor 28 over to the opposite trolley wire by means of collector 9 and contactor 10 after collector 9 has engaged contactor 10. Since the other actuating coil 11 is in parallel with the coil just described, its circuit will be through conductors 18, 18a, 22, 22 and the coil 11, conductor 21 and switch 26 through to conductor 28 to the opposite trolley wire by means of contactor 10 and collector 9, it being understood, of course, that by the time this circuit is completed collector 9 has gone into engagement with the contactor 10 as previously explained.

Attention is at this point invited to the fact that resistance 23 is of a comparatively high value. The reason for this is that it will be able to withstand rated voltage, usually 600 v., without burning out. When the frogs are to remain in the straight through position both collectors will substantially simultaneously engage the respective contactors thereby imposing full voltage across 23 which is in series with the switch 26. In view of the high resistance only a small current will be drawn during the interval of contact between collectors 9, 9a and contactors 10, 10a.

It has been pointed out before that the tongue elements 7, 7 are restored to the straight through position by means of the re-set mechanisms 12, 12 following the passage of the vehicle underneath the trolley frogs. During the approach of the vehicle, assuming that it is to continue on the straight ahead path, both collectors 9 and 9a will at substantially the same time engage their respective contactors 10 and 10a which action will prevent the shifting of switch 26 because a circuit will be established across the line between the contactors 10 and 10a by means

of conductors 18, 18a, resistance 23, conductor 27, switch 26 and conductor 28. This effectively shunts out coil 24 and prevents its actuation.

Assuming that the vehicle approaching the frog pans 1 and 2 is to turn off on wires 4, 4 then collector 9a will engage contactor 10a a sufficient time ahead of the engagement of collector 9 with contactor 10 to establish the operating circuit for coil 24, described above. Then by the time collector 9 has engaged contactor 10, switch 26 will have been shifted to the dotted line position thereby closing the circuits through coils 11, 11 and shifting tongues 7, 7 to the turn-off position. When collector 9a breaks contact with contactor 10a the holding circuit for coil 24 will be broken, thereby shifting switch 26 back to the full line position and deenergizing coils 11, 11 such that when collectors 9 and 9a engage reset mechanisms 12, 12 the tongues 7, 7 will be shifted to the straight through position. It is necessary, however, that both contactors 10, 10a be in engagement with their respective collectors 9, 9a before coils 11, 11 are energized. The action just previously described gets the circuit ready for closing by contactor 10 engaging collector 9.

A modification of the above structure is disclosed in Figs. 2, 3 and 4 in which frog pans 26 and 27 are provided to which trolley wires 29, 29 are secured and from which trolley wires 30 and 30 branch off, as shown, and from which trolley wires 31, 31 lead off for the straight through position. Each of the frog pans 26 and 27 is provided with shiftable tongue elements 32, 32 pivoted at 33, 33 to guide current collectors 9, 9a selectively on to the straight through wires 31, 31 or the turn-off wires 30, 30.

Means have been provided for mechanically resetting the tongue elements 32, 32 to the straight through position after the passage of the vehicle on the turn-off position and it employs mechanism similar to that described above which constitutes re-set levers 35, 35 which are connected by means of linkages 36, 36 to the plungers 37, 37 of coils 34, 34 and the opposite end of the plungers 37, 37, is connected to the linkage 56 fixedly secured at one end to the shiftable tongue elements 32, 32. The members 56, 56 are held in position by latches 40, 40 fixed to bars 40a, 40a pivoted at 39, 39 cooperating with springs 38, 38 that hold latches 40, 40 in retracted position in the same manner as springs 17, 17 above.

Attention is invited to the fact that in the modifications, the control coils, switch and resistance 23, 24 and 26 have been replaced by simple make and break switches 41 and 42, that are actuated by tiltable or pivoted contactor elements 46 and 47. Attention is further invited to the fact that each of these contactors 46 and 47 is of varying length, as indicated by the distance "A" which is determined in a manner similar to the distance "A" described in connection with Fig. 1 above. Any vehicle approaching the trolley frogs and

desiring to go on the branch trolleys 30, 30 will be positioned underneath the trolley frogs such that collector 9a will be considerably advanced ahead of the collector 9 for reasons set forth above and will, as a result, engage the contactor 46 before collector 9 engages contactor 47. Upon collector 9a engaging contactor 46, it will elevate it and simultaneously close switch 41. The closing of switch 41 establishes a circuit through the actuating coils 34, 34 by means of conductor 43, coil 34, conductor 44 and a second coil 34 and

conductor 45 through switch 42 and thence to the opposite trolley wire 28. This action will shift the tongue elements 32, 32 to the turn-off position and permit the collectors 9 and 9a to follow the path of trolley wires 30, 30. As soon as the collector 9 engages its corresponding contactor 47, it will break the circuit by reason of it opening switch 42 thereby deenergizing coils 34, 34 and when the collectors 9, 9a engage the re-set mechanisms 35, 35, the tongue elements 32, 32 will be 10 restored to their straight through position. Attention is invited to the fact that switch 41 is normally open and switch 42 is normally closed.

Distance "B" in Fig. 3 shows the distance contactor 46 is pivoted ahead of contactor 47. The reason for this displacement is that if collector 9 should disengage contactor 47 before 9a disengages 46 there would be a shifting of the tongue elements causing a false or undesired operation of the frog. By advancing the pivot 50 of contactor 46 switch 41 will open before switch 42 is closed and thereby prevent an undesired operation.

Assuming that the vehicle with collectors 9 and 9a desires to continue in the straight ahead position on to wires 31, 31, it should be observed that collectors 9, 9a will approach and practically, substantially, simultaneously engage the respective contactors 46 and 47, and whereas collector 9a in its movement will close switch 41 thereby normally closing the shifting circuit, yet before the coils 34, 34 can be energized the circuit will have been broken by collector 9 engaging contactor 47 thereby breaking the shifting circuit. It should be apparent from this description that the functioning of the actuating coils 34, 34 is not dependent upon the opening or closing of any switch by a coil or upon a potential being imposed across an arbitrary resistance and even if any arcs are formed between the collectors 9, 9a and their respective contactors, they will not influence in any way the functioning of the device. Furthermore, since the engagement of contactors 46 and 47 with collectors 9 and 9a, is a strictly mechanical function the possibility of arcing will, as a natural result, be prevented and the shifting of the tongue elements will be entirely dependent, therefore, upon the mechanical action of the contactors and the respective collectors. As previously indicated, the space or distance A', which represents the difference in effective length of the respective contactors subtracted from the lag of collector 9 behind 9a, affords the space-time interval in which coils 34, 34 can shift the respective tongue elements 32, 32 to the turn-off position before contactor 47 is shifted by collector 9 thereby breaking the circuit at switch 42.

Figs. 2 and 4 disclose in a little greater detail the functioning and construction of the switches 41, 42 and their relationship to the contactors 46 and 47, it being observed as previously indicated that the two contactors are of different lengths. Each of the contactors 46 and 47 comprises initially a pivoted arm 59 as indicated whose pivot pin 50 is fixed in the tip of the frog pan 26. The right-hand end of the contactor may be variously angled, such as to vary the opening or closing time of the respective switches 41 and 42. The distance or length, indicated "X," of the contactor lies in a single straight line or plane and is of such an extent that there will be ample time, during passage of a vehicle, for the collector to hold the contactor in an elevated position for the coils 34, 34 to function thereby shifting tongues 70

32, 32 to the turn-off position by means of plungers 37, 37. The contactor arm 46 is further provided with a cross member 48 that rests upon the trolley wire 28 and prevents the contactor arm 5 from dropping too far below the horizontal plane of trolley wires 28, 28. After the passage of the collector, each of the contactors 46, 47 is restored to their initial position as shown in Fig. 4 by means of gravitational action.

Fixed to the tip of frog pan 26 is a bracket element 51 that is substantially H-shaped and in which the cross element of the H more or less snugly engages with the upper portion of the projection on tip 26 and by placing the pivot pin 59 through the apertures provided in the bracket element 51 and in the tip, it will hold the two in a firmly fixed relationship and render the two elements immovable with respect to each other. For the convenience of securing 59 on pin 50, it is provided with ears 59, 59a and the entire assemblage is held in place by means of a pair of conventional cotter pins. Fixed to the left-hand end of the contactor arm 59 is a bracket 49 secured thereto by welding or any other conventional mode of attachment. Bracket 49 is pivoted with respect to a switch holder 54 by means of a pin or pintle 53 fixed in the switch holder 54. Holder 54 is pivoted with respect to bracket 51 by means of pins 52, 52. Secured to the upper part of the switch holder 54 is switch 41 and in the particular illustration this is shown as a mercury switch, although any other form of switch may be substituted in lieu thereof. The switch 41 is fastened to the holder 54 by means of an appropriate clamping element 55. It should be evident from an inspection of the structure set forth in Figs. 2 and 4 and from the description above that as the contactor arm 46 is elevated by its corresponding current collector 9a that it will pivot about the pin 50, and bracket 49 engaging with pin 53 by means of its slotted end, as shown, will tip holder 54 to a forward position, causing the mercury in the switch 41 to engage or close the circuit through the leads 57 and 58 that correspond to conductor 43 connecting to the one end of switch 41 and the other representing the connection to the trolley 28. Mechanism used in conjunction with contactor 47 may be identical with that of contactor 46 with the exception that the switch 42 would be normally closed when holder 54 holds switch 42 in the horizontal position, and when the contactor 47 is elevated by the collector 9, the switch 42 is brought to a tilted position by the holder 54 but would open the circuit with respect to the leads 57 and 58 that are fastened in the switch element 42. The mechanical functioning of the two devices is substantially the same. It must be borne in mind in any event that under normal conditions switch 41 is open and switch 42 is closed.

In each of the disclosures above, it is very essential that the respective lengths of contactors 10 and 10a and 46 and 47 be proportioned such that irrespective of the angle of the turn-off, the coils 11, 11 and 34, 34 will have ample time to become energized to thereby permit the shifting of the tongue elements to the turn-off position. It is thought apparent, therefore, that a trolley shifting mechanism has been provided that is positive in its action and will prevent any unintentional shifting of the tongue elements and that is simple and economical in its construction and maintenance.

75 A structural variation of the embodiment of

Fig. 1 is set forth in Fig. 5 in which the device is normally set for curve operation and is shifted to straight line and thereafter resets to curve operation. Structures of this type are used at such places where the bulk of traffic turns off and only a small percentage continues straight through. The structure detail of Fig. 5 appearing in Fig. 1 has been designated by primed numbers and since the circuits involved vary slightly from that of Fig. 1 different numerals have been assigned to circuit parts in order to more easily point out the operation.

As previously recited, tongue elements 7', 7' are normally set for curve and they are shifted only when a straight through travel is desired. Consequently, plungers 14', 14' will be positioned such that the bars or linkages 15', 15' are held to the right of latches 15a', 15a' and when the coils are energized they will draw the plungers 14', 14' to the left and move the tongues 7', 7' to the straight through position. Reset mechanisms 12', 12' will restore the tongues 7', 7' to curve after passage of collectors 9a', 9'; the reset devices 12', 12' being connected to plungers 14', 14' by linkages 13', 13'.

Assume a vehicle carrying collectors 9', 9a' is approaching the switch or frog pans 1', 1' and it is intended to have them turn off on wires 4', 4', the collectors 9', 9a' will substantially, simultaneously engage contactors 10', 10a' which will establish a circuit including contactor 10', conductor 63, resistance 23', conductors 64 and 67, switch 26', conductor 66 and contactor 10a'. This effectively shunts out coil 24' and prevents the shifting of switch 26' to the dotted line position and preventing the energization of coils 11', 11'.

If the vehicle carrying collectors 9', 9a' is to continue straight ahead then collector 9' will first contact contactor 10' and this will establish a circuit through coil 24' by means of conductors 63, 64 and 60 including resistance 23'. Switch 26' will then be shifted to the dotted line position. Distance A' is required to be of such length that there will be ample time for coil 24' to be energized to shift switch 26' to the dotted line position and upon 9a' contacting 10a' a circuit is established through coils 11', 11' including contactor 10', conductors 62, 61, 65, switch 26' and conductor 66, and thence to contactor 10a'. The contactors 10a' and 10' have to be of such length as to enable coils 11', 11' to become fully energized such that plungers 14', 14' may move bars or linkages 15', 15' to the opposite sides of latches 15a', 15a' and shift tongues 7', 7' to the straight through position. As previously indicated, reset mechanisms 12', 12' will restore the tongues to their curve position.

The operation of all parts of the structure is identical with that of Fig. 1 except as to the order of operation.

It should be evident that since the construction of Fig. 1 may be normally set to the curve position by the changes shown in Fig. 5, that a corresponding alteration of Fig. 3 will enable it to be normally set to curve.

That which is regarded new, novel and useful and which is sought to be protected by Letters Patent of the United States is as follows.

I claim:

1. In a trolley switching system; a pair of frog pans held in a spaced relationship; a shiftable tongue on each of said pans; a single uni-directional acting coil on each of said pans to shift said tongues in one direction; straight through trolley wires connected to each of said pans and

one pair of trolley wires branching off of said straight through wires; contactors associated with the trolley wires on the approach side of said pans substantially equidistant therefrom, one of said contactors being of greater length than the other; a control circuit for said coils; a relay contact in said control circuit; a circuit controlling said relay and including a resistance element; said relay actuatable from the shorter of said contacts and adapted when said shorter one is contacted by a current collector engaging its associated trolley wire prior to a cooperating collector engaging said longer contact and its associated trolley wire to close said coil circuit, such that when said longer contactor is subsequently engaged by the collector engaging its associated trolley wire prior to disengagement of the collector with said shorter contactor it will complete said coil circuits to shift said tongue elements; and mechanically actuated reset means to shift said tongue elements back to their original position following passage of said collectors.

2. In a trolley shifting device; a pair of frog pans held in spaced relationship; a pair of trolley wires connected to one end of each of said pans and two pairs of trolley wires connected to the other end of said pans; a shiftable tongue element associated with each of said pans; a single uni-directional acting coil associated with each of said pans; plungers in each of said coils linked to said tongues; a contactor associated with each wire of said pair of trolley wires substantially equidistant from said pans; one of said contactors being of greater length than the other but in which the trailing ends thereof are in transverse alignment; means to shift said tongue elements including a circuit in which said coils are adapted to be connected across said trolley wires; a control circuit for said means including a relay and a resistance connectable in series with said relay adapted to connect said coils across said trolley wires, said resistance connectable across said contactors during normal operation; a pair of vehicle supported current collectors engageable with said pair of trolley wires; said short contactor being first engaged by a collector when said vehicle is turning thereby actuating said relay such that when said other collector engages the longer contactor the coil circuit will be closed, the respective lengths of said contactors determining the length of time said coils are connected to said trolley wires, thereby shifting said tongue elements; and reset means engageable by said collectors acting through said plungers to shift said tongue elements to their original position following passage of said collectors.

3. In an overhead trolley system; a pair of pan elements each including a shiftable tongue element; trolley wires associated with the approach side of said pans; contactors associated with said trolley wires; current collectors movable along said trolley wires engageable with said contactors; a uni-directional coil and plunger device on each of said pans to shift said tongue elements; a circuit for said coils including a switch and connectable across said trolley wires; a control circuit for said circuit which includes a resistance and a coil to actuate said switch; said control circuit energized when one of said collectors engages its corresponding contactor ahead of the other and adapted to shift said switch to said coil circuit, said plungers and coils energized only after both said contactors are en-

gaged by said collectors; and when said contactors are engaged substantially simultaneously by said collectors said switch coil being shunted by said switch whereupon said resistance and said switch are connected in series and across said contactors thereby preventing energization of said coil.

4. In an overhead trolley system; a pair of frog pans having shiftable tongues thereon; a trolley wire connected to the approach end of said pans and having straight through and curve wires attached to the other end of said pans; said tongue elements being normally set to curve position; a single acting electromagnetic means on each pan to shift said tongues to straight through position; a control circuit for said electromagnetic means, including a relay and a resistance; contactors associated with the approach side trolley wires; collectors slideable along said wires; one of said collectors engaging one of said contactors to establish a circuit through said circuit through said relay and resistance to shift the switch controlled by said relay such that only when the other of said collectors engages the other of said contactors said electromagnetic means will be energized to shift said tongues to straight through position, and when both said contactors are simultaneously engaged by both said collectors a circuit is established through said resistance to shunt out said relay; and reset means acting through said elec-

30
5
10
15
20
25

tromagnetic means to restore said tongues to curve position.

5. In an overhead trolley system; a pair of frog pans held in spaced relation; a shiftable tongue on each pan; a trolley wire connected to the approach end of each pan and a curve and straight through trolley wire connected to the other end of each pan; said tongues normally set to curve position; a uni-directional solenoid and plunger mounted on each pan, said plungers connected to said tongue elements; a circuit for said solenoids including a relay switch; a control circuit for said relay including a resistance element; a contactor associated with each approach trolley wire; collectors slideable along said trolley wires; said tongue directing said collectors along said curve or straight through trolley wire; said switch shunting said relay when both contactors are simultaneously engaged by said collectors, and when one of said collectors engages its corresponding contactor ahead of the other a circuit is established through said relay and said resistance thereby shifting said switch such that only when both collectors engage both said contactors said solenoids will be energized to thereby shift said tongues to straight through position and means acting through said plungers to return said tongues to curve position after passage of said collectors.

WARREN J. LEWIS.
